UNITED STATES PATENT OFFICE.

GEORGE H. PEAL, OF RUTHERFORD, NEW JERSEY.

PYROTECHNICAL TOY.

1,246,315.

Specification of Letters Patent. Patented Nov. 13, 1917.

Application filed August 31, 1915. Serial No. 48,188.

To all whom it may concern:

Be it known that I, GEORGE H. PEAL, residing at Rutherford, in the county of Bergen and State of New Jersey, have invented 5 certain new and useful Improvements in Pyrotechnical Toys, of which the following is a specification.

This invention relates to a pyrotechnical toy and although it is particularly adapted 10 for use in the construction of toy fire crackers or the like, it may, however, be employed in connection with other devices.

The object of the invention is to provide a toy, in the nature of a fire cracker or the like, 15 which may be used at celebrations of various characters, and which will be entirely harmless.

A further object is to provide a toy of the type indicated which may be used as a 20 "favor" at parties, banquets, or other gatherings.

A further and more detailed object is to provide a package made up of a hollow casing containing a detonating device in the 25 form of a "snapper," the package containing also a gift or "prize" usually made up of tissue paper or the like. To connect one side of the "snapper" with a "fuse" and to connect the opposite side of the "snapper" 30 with the casing, and to inclose the casing in a wrapper adapted to hold one side of the snapper connected to the casing. The general appearance of the package with the wrapper in place and the "fuse" projecting 35 from one end being such as to strongly resemble a fire cracker, and the "fuse" and casing serving as opposite hand grips whereby the "snapper" may be readily detonated.

Other objects and aims of the invention, 40 more or less specific than those referred to above, will be in part obvious and in part pointed out in the course of the following description of the elements, combinations, arrangements of parts and applications of 45 principles, constituting the invention; and the scope of protection contemplated will be indicated in the appended claims.

In the accompanying drawings which are to be taken as a part of this specification, 50 and in which I have shown a merely preferred form of embodiment of the invention:

Figure 1 is a perspective view of a finished article constructed in accordance with 55 the provisions of this invention.

Fig. 2 is an enlarged longitudinal central sectional view.

Fig. 3 is a transverse sectional view taken upon the plane of line III—III of Fig. 2.

Fig. 4 is a perspective view of the "snapper" 60 detached; and

Fig. 5 illustrates a modification.

Referring to the drawings for a detailed description of the construction illustrated, the reference character L indicates the casing. This may be made up in any preferred manner, but preferably comprises a rectangular sheet of paper or thin cardboard wound upon itself in the manner best seen in Fig. 3. One or both sides of the paper 70 forming the casing may be printed or ornamented with the congratulatory, patriotic, comical, or other verse or character of ornamentation which may be read or inspected with pleasure by the person who 75 opens the device.

The reference character G indicates the "snapper." This is made up of two separate members as indicated in the drawing by the reference numerals 1 and 2. The 80 members 1 and 2 are formed of tough cardboard or other suitable material and are arranged so that their end portions overlap, as indicated in Fig. 4. Between the overlapping surface portions a suitable detonating cap or the like, as 3 is arranged. At least one of the over-lapping surface portions is provided with a sanded or roughened surface 4. A binding medium, indicated as 5, is employed for holding the 85 over-lapping portions in close juxtaposition but at the same time permitting them to slide relatively to each other when drawn forcefully in opposite directions, as will be presently referred to.

The reference character H indicates the "prize." It may be in the form of a flag, small tissue paper favor, or other approved article. It is folded or pressed into a small compass and is connected to one of the members of the "snapper" as shown in Fig. 2. The part H with the "snapper" attached, is placed within the casing, or rather the sheet of the paper forming the casing is wound tightly about the part H and the "snapper." 105

The lower end, as 2, of the "snapper" is allowed to project through the opening in the lower end of the casing. The other member, as 1, of the "snapper" is folded upon itself within the casing and a "fuse" member as 6 is connected in the fold as at 7.

The presence of the casing serves to positively maintain the member 1 of the "snapper" in a folded condition so as to effectively

retain the "fuse" member against detachment. Where, however, a stronger attachment for the "fuse" member is desired, the same may be bound tightly to the member 1 by fine wire or other suitable means, as indicated at 8.

The lower projecting portion of the member 2 of the "snapper" is folded upon itself about the lower edge of the casing and over 10 upon the exterior surface of the casing. It is held in this position by means of the wrapper 9.

The wrapper may be of any suitable material, but preferably comprises a rectangular sheet of paper, usually a colored tissue paper. It is somewhat wider than the length 15 of the casing L and is wound about the casing and tucked in at the opposite ends, substantially as indicated, so as to maintain the 20 casing in a wound condition about the part H and the "snapper." The tucked-in portions of the wrapper, as 10, serve to close the ends of the casing.

The modification Fig. 5 is substantially 25 the same in all respects as the construction shown in the other views, except that the separately formed "fuse" member is omitted, and in its stead the upper member of the "snapper" is projected through the upper 30 end of the casing to form a "fuse" member of itself, as indicated at 11. For this purpose the projecting portion of this member of the "snapper" should be made of paper or the like, twisted or otherwise operated 35 upon to resemble a "fuse."

Both in the modification, as well as in the other figures, the part H may or may not be rigidly connected to the "snapper." Where 40 it is rigidly connected to the "snapper," however, it is preferably connected to the member 1 thereof so that it will be withdrawn from the casing when the "fuse" is 45 pulled out. For this reason the part H may be constructed as a separate package in itself it being provided with an independent 50 wrapper, as 12, by means of which it may be connected with the part 1 of the "snapper" by the use of glue or by other medium.

As many changes could be made in this 55 construction without departing from the scope of the following claims, it is intended that all matter contained in the above description or shown in the accompanying drawing shall be interpreted as illustrative only and not in a limiting sense.

While I have shown and hereinabove described a particular type of detonating device, it will, however, be apparent that any other kind of detonating device may be employed, so long as it is adaptable to being detonated or sounded by relative movement as between the casing and the "fuse" member or hand grip.

In operation the casing is gripped in one 65 hand and the fuse or hand grip is drawn up-

wardly from one end of the casing. With the type of detonating device illustrated, the roughened surface 4 will be drawn across the cap 3 and will cause the cap to be exploded. The member 1 of the "snapper" 70 or detonating device will be drawn entirely out of the end of the casing and will carry the "prize" H with it. The tucked-in end of the wrapper will readily give way to the outward movement of the parts referred to. 75 Thereafter the wrapper 12 of the "prize" may be broken and the "prize" readily unfolded. The paper forming the casing may then be opened and any other contents of the casing readily obtained, or the printed 80 matter upon the casing itself may be inspected.

Having thus described my invention what I claim as new and desire to secure by letters Patent is:

1. A device of the class described, comprising a casing, a detonating device arranged within the casing, said detonating device having parts movable in opposite directions to produce a detonation, one of the 90 parts of the detonating device having a portion engaging about the lower edge of the casing and the other of the parts of the detonating device having a hand grip connected thereto projecting out of the upper 95 end of the casing.

2. A device of the class described, comprising a casing, a detonating device arranged within the casing, said detonating device having parts movable in opposite directions to produce a detonation, one of the parts of the detonating device having a portion extending out of the lower end of the casing and over upon the exterior surface of the casing, means for retaining said last 105 mentioned portion in position upon the exterior surface of the casing, and a hand grip member connected to the other member of the detonating device projecting out of the upper end of the casing.

3. A device of the class described, comprising a casing, a detonating device arranged within the casing, said detonating device having parts movable in opposite directions to produce a detonation, one of 115 the parts of the detonating device having a portion extending out of the lower end of the casing and over upon the exterior surface of the casing, a wrapper for the casing closing the opposite ends thereof and serving to retain the last mentioned portion of the detonating device in position upon the exterior surface of the casing, and a hand grip connected to the other member of the detonating device.

4. A device of the class described, comprising a detonating device formed of a pair of members movable in opposite directions to produce a detonation, an open ended casing within which said detonating 130

device is arranged, a wrapper for the casing serving as means for retaining one of the members of the detonating device fixed to the casing, and a hand grip provided upon 5 the other member of the detonating device.

5. A device of the class described, comprising a detonating device formed of a pair of members movable in opposite directions to produce a detonation, an open ended 10 casing within which said detonating device is arranged, a wrapper for the casing closing the opposite ends of the casing and engaging a portion of one of the members of the detonating device to hold the same fixed 15 to the casing, and a hand grip projecting out of the upper end of the casing, said hand grip being connected to the other member of the detonating device.

6. A device of the class described, comprising a detonating device formed of a pair of members movable in opposite directions to produce a detonation, an open ended casing within which said detonating device is arranged, said casing being formed 25 of a rectangular sheet of material wound upon itself into cylindrical formation, one of the members of the detonating device being folded upon itself and over against the outer surface of the casing, a wrapper 30 for the casing serving to maintain the same in a wound condition, said wrapper having portions tucked into the ends of the casing to close said ends, said wrapper also covering and concealing the last mentioned portion 35 of the detonating device and serving to hold the same in position upon the exterior surface of the casing, and a hand grip connected to the opposite member of the detonating device.

40 7. A device of the class described, comprising a detonating device formed of a pair of members movable in opposite directions to produce a detonation, an open ended casing within which said detonating device is arranged, means whereby one of 45 said members is fixed to the casing, a hand grip fixed to the other of said members and projecting out of one end of the casing, and a "prize" package within the casing connected 50 to the last mentioned member of the detonating device and movable therewith.

8. A toy fire cracker, comprising a body member and a "fuse" member, a detonating device carried by the body member, means 55 whereby the detonating device may be detonated by drawing outwardly upon the "fuse" member, and a "prize" package within the body connected to the fuse member to move outwardly therewith.

9. A device of the class described, comprising a casing, a detonating device arranged within the casing, said detonating device comprising a part folded upon itself, a hand grip member connected to said part by being caught in the fold thereof, and the 60 casing serving to retain said part folded.

10. A device of the class described, comprising a detonating device formed of a pair of members movable in opposite directions to produce a detonation, an open ended 65 casing within which said detonating device is arranged, a hand grip member, means whereby the casing serves to retain the hand grip member attached to one of the members of the detonating device, and a 70 wrapper for the casing serving as means for retaining the other member of the detonating device attached to the casing.

11. A device of the class described, comprising a detonating device formed of a 75 pair of members movable in opposite directions to produce a detonation, an open ended casing within which said detonating device is arranged, a hand grip member, means whereby the casing serves to retain 80 the hand grip member attached to one of the members of the detonating device, and means for retaining the other member of the detonating device attached to the casing.

12. A device of the class described comprising, a casing, a separately formed detonating device made up of two members movable in opposite directions, one of said members having a roughened surface part 85 within the casing, the other of said members having a detonating cap fixed thereto and disposed in direct engagement with the roughened surface of the other member, binding means extending about parts of 90 said two members to retain said detonating cap normally in direct engagement with said roughened surface but being of a character to permit movement of the detonating cap relatively to the roughened surface when 95 force is applied to move said members in opposite directions whereby to permit detonation of said cap, one of said members extending beyond the binding means and having a part fixed to the casing, and the other of said members having a part also 100 projecting beyond the binding means and providing a hand grip beyond the casing.

In testimony whereof I affix my signature in the presence of two witnesses.

GEORGE H. PEAL.
